METHOD FOR MAKING TIE PLATES

Thomas E. Lewis, Jr., Johnstown, Pa., assignor to United States Steel Corporation, a corporation of New Jersey

Application January 7, 1953, Serial No. 329,952

1 Claim. (Cl. 29—16)

This invention relates to the manufacture of tie plates and, in particular, to the hot-forging of a tie-plate blank to form from the material thereof a hook or lug upstanding from one face of the plate, adapted to engage the flange of a rail supported by the plate.

Tie plates are used in large numbers and economy in the manufacturing cost is important because of the competitive condition of the market. It is the object of my invention, therefore, to provide a method and apparatus whereby tie plates may be produced at a lower cost than heretofore. A further object is the production of a more uniform and accurately dimensioned tie plate than that resulting from the practice previously employed.

In a preferred practice of the invention, I shear flat bar stock to length and punch the spike holes therein, thus forming a blank. I then heat one end of the blank to forging temperature and subject it to a punching operation to displace partially from the blank the metal required to form the hook or lug. Thereafter, I subject the displaced lug to a forging operation in a press, thereby bending and shaping it to final form. The blank is thus converted into a tie plate which is finished except for a few minor additional operations such as a final shaping, cold flattening and burr removal if necessary.

The apparatus which I have devised for carrying out the above method includes a split die box having means for opening and closing it, and two separate punches adapted to cooperate therewith successively in effecting the two stages of the method, i. e., initial punching and final shaping. The die is conveniently mounted on the platen of a conventional punch press and I provide special means for removably attaching the punches to the ram thereof. This apparatus is claimed in my application Serial No. 548,383, filed May 11, 1956, which is a division hereof.

A complete understanding of the invention may be obtained from the following detailed description and explanation which refer to the accompanying drawings illustrating the present preferred embodiment and practice.

In the drawings,

Figure 1 is a plan view of a base plate with the die and means for operating it mounted thereon;

Figure 2 is an elevation showing the die and the first punch for cooperating therewith mounted on a press ram;

Figure 3 is a central vertical section through the ram and die with the first punch in place on the ram;

Figure 4 is a horizontal section through the press ram and punch, taken along the plane of line IV—IV of Figure 3;

Figure 5 is a partial side elevation of the tie-plate blank after the first or punching operation;

Figure 6 is a view similar to Figure 3 showing the second punch for effecting the shaping or forging operation on the lug or hook, in conjunction with the die;

Figure 7 is a view similar to Figure 5 showing the blank after the second or forging operation;

Figure 8 is a similar view showing the finished tie

2

plate after an optional final shaping of the hook or lug; and

Figure 9 is a plan view of a finished tie plate.

Referring now in detail to the drawings and, for the present, particularly to Figures 1 through 4, a base plate 10 is adapted to be secured in position on the platen of a punch press by bolts 11. Blocks 12, 13 and 14 are secured to the base plate in any desired manner and define a pocket accommodating a die box 15 which is split on a central, vertical, longitudinal plane. The die halves are machined to provide cavities therein which match when abutted to form a closed recess. A set screw 16 holds the rear half of the die box in place. The front half is secured to a block 17 provided with a vertical slot 17a to accommodate the head of a screw 18 which is threaded through a nut 19 upstanding on plate 10 and fixed thereto. A crank 20 on the outer end of the screw permits it to be turned manually so as to retract the front half of the die quickly from the fixed rear half or set it firmly thereagainst.

A supporting block 21 is secured to plate 10 with its top surface in the same horizontal plane with those of blocks 12 and 14. An L-shaped gage plate or stop 22 is secured to blocks 12 and 21 and has a block 23 thereon provided with an overhanging lip 23a. The gage plate serves to position accurately a tie-plate blank 24 when laid on blocks 12 and 21 and pushed home against the inner edges of the plate as shown in Figures 1 and 2. An anvil 25 secured to the plate 10 adjacent block 12 has one end 26 overhanging. The end 26 is finished square but the lower surface thereof has a predetermined taper as shown at 26a in Figure 2.

The ram of a punch press indicated at 27 has a recess in its lower end to accommodate a seating block 28 held in place by set screws 28a. Block 28 has a socket in its lower face to receive the upstanding reduced and tapered neck 29 of a punch 30. Block 28 also has a transverse bore therethrough in which a locking pin 31 is slideable. The outer end of the pin is supported by a bearing bracket 31a secured to the ram. The pin has a stop collar 31b thereon adapted to engage the bracket 31a and limit outward movement of the pin. The neck 29 of punch 30 has a hole therethrough which alines with the bore in the seating block 28 when the punch neck is bottomed in the recess in the block. The pin 31 thus serves, when pushed in after positioning the punch, to lock the latter firmly in place.

As best shown in Figures 2 and 3, the lower portion of punch 30 is shaped and finished to displace, push down or express from a tie-plate blank 24, through the lower face thereof, a tongue 32 (see Figure 5). This it accomplishes by shearing the metal of the blank about three sides of the opening in die box 15, leaving the resulting tongue integrally united with the blank at the fourth side, and bending the tongue downwardly about said fourth side. A punch 33 shown in Figure 6, is similar in general to punch 30 but is shaped to effect a shaping or forging operation on the tongue in die box 15, to form it into a hook or lug 34 (see Figure 7), the lower face 60 of the punch having the shape desired on the surface of the lug which is underneath when the tie plate is in position of ultimate use. Punch 33, of course, is inserted in the block 28 after the first punching operation, in lieu of punch 30.

65 The method of my invention will now be explained in greater detail. It will be recalled that the shearing of bar stock to length and the punching of the spike holes therein has already been mentioned. Thereafter the resulting blanks are heated at one end to forging temperature. A blank when heated is laid on blocks 12 and 21 with its heated end over die 15, and pushed against both inner edges of gage 22. With punch 30 in position on

ram 27 as shown in Figure 2, the punch press is operated to cause a downward stroke of the ram. This drives punch 30 through the blank, causing the shearing and displacement of tongue 32 downwardly into die box 15 (Figure 6) as just explained, and imparts a slight initial bend thereto.

When the press ram is retracted, leaving the blank in position on blocks 12 and 21, pin 31 is pulled back, punch 30 is removed and punch 33 is inserted in its place and locked by restoring the pin to its innermost position. The press ram is then operated again. The second stroke of the press ram causes the punch 33 to enter the hole in the blank formed by punch 30, and to forge and bend tongue 32 into the hook or lug 34 (Figure 7). The top and sides of the lug are shaped by the bottom and sides of the cavity in die box 15. The finished lug has a vertically extending portion 35 and a generally horizontal portion 36 extending at an angle thereto somewhat greater than 90°. The latter portion, of course, is adapted to engage the top of the rail flange when butted firmly thereto. The lip 23a on block 23 prevents the blank from rising with the ram as it is retracted, should there be any tendency for it to do so. The quick locking and unlocking action of pin 31 permits the changing of the punches and the accomplishment of the initial punching and the final forging of the lug on the same heat, since there is but little cooling of the blank between strokes of the press.

To remove the blank, crank 20 is operated to open the die box 15. Thereafter, crank 20 is again operated to close the die box and punch 33 is replaced by punch 30, whereupon the apparatus is ready for another operating cycle.

If it be desired that the interior surfaces of these portions 35 and 36 intersect to form a sharp dihedral angle instead of leaving a small radius or fillet therebetween as shown in Figure 7, such result may be easily achieved by means of anvil 25. To this end, when the blank is removed from the die, after turning crank 20 to retract the movable forward half thereof, it is placed on the anvil 40 with the lug down, i. e., without turning it over, and to the left of the tapered overhanging end 26 of the anvil. The blank is then given one or two sharp pulls by the tongs in which it is held, seating the interior faces of the lug forcibly against the square-finished tapered end 26 of the anvil. The angle of this taper is the angle desired 45 between the under surface of the finished lug portion 36 and the body of the plate. This final shaping operation leaves the lug in the condition shown in Figure 8 and completes the hot-forging of the blank which is then permitted to cool for finishing operations such as cold flattening and burr removal, if necessary, preparatory to inspection and shipment.

It will be apparent from the foregoing that the invention is characterized by important advantages over known methods of making tie plates. In the first place, the output per man-hour is increased materially. In addition, the prescribed tolerances for finished dimensions may be more readily maintained and a high degree of uniformity in the shape, location and disposition of the lug is achieved without extra care or special precautions.

Although I have disclosed herein the preferred practice of my invention, I intend to cover as well any change or modification therein which may be made without departing from the spirit and scope of the invention.

I claim:

In a method of making a tie plate having an upstanding lug including a substantially vertical portion and an end portion bent over therefrom to engage the top of a rail flange resting on the plate, the steps including heating a length of flat metal bar to forging temperature, driving into one of the wider faces of the bar and out through the other and into a closed die box, a punch having a bottom sloping downwardly from one side to the other, thereby expressing from said other face of the bar and bending downwardly therefrom a substantially straight tongue united with the bar at one end only and sloping downwardly from said end but spaced above the bottom of the box, then striking the tongue through the hole in the bar formed by said punch, with a second punch of a contour corresponding to the bottom of the box and effective to forge said tongue against the bottom of the box and thereby bend the portion of the tongue nearest the bar to a position substantially at right-angles thereto and the remainder of the tongue to a position at an acute angle to the bar, thus forming said tongue into said lug.
